UNITED STATES PATENT OFFICE

161,911

CIGARETTE LIGHTER

Paul W. Felt, St. Paul, Minn., assignor to Brown & Bigelow, St. Paul, Minn., a corporation of Minnesota

Application June 8, 1950, Serial No. 10,414

Term of patent 14 years

(Cl. D48—27)

To all whom it may concern:

Be it known that I, Paul W. Felt, a citizen of the United States, residing in St. Paul, county of Ramsey, and State of Minnesota, have invented a new, original, and ornamental Design for a Cigarette Lighter, of which the following is a specification, reference being had to the accompanying drawing, forming part hereof, in which:

I claim:

The ornamental design for a cigarette lighter, as shown.

PAUL W. FELT.
